US00D791419S

(12) **United States Design Patent** (10) **Patent No.:** **US D791,419 S**
(45) **Date of Patent:** **** Jul. 4, 2017**

(54) **WASHING MACHINE**

(71) Applicant: **Samsung Electronics Co., Ltd.**, Suwon-si, Gyeonggi-do (KR)

(72) Inventors: **Kangdoo Kim**, Seoul (KR); **Yeonsu Kim**, Seoul (KR); **Jungeun Park**, Seoul (KR)

(73) Assignee: **SAMSUNG ELECTRONICS CO., LTD.**, Gyeonggi-Do (KR)

(**) Term: **15 Years**

(21) Appl. No.: **29/560,280**

(22) Filed: **Apr. 5, 2016**

(30) **Foreign Application Priority Data**

Nov. 20, 2015 (KR) 30-2015-0058639

(51) **LOC (10) Cl.** **15-05**

(57) **CLAIM**

The ornamental design for a washing machine, as shown and described.

DESCRIPTION

FIG. 1 is a perspective view of a washing machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the washing machine that form no part of the claimed design.

1 Claim, 7 Drawing Sheets
